Primary Examiner — Jennifer L Watkins

Assistant Examiner — Samantha Lynne Brodowski

(57) **CLAIM**

The ornamental design for a card wallet, as shown and described.

DESCRIPTION

FIG. 1 is a first perspective view of a card wallet showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof

FIG. 8 is a bottom view thereof;

FIG. 9 is an enlarged view of the selected portion in FIG. 1;

FIG. 10 is an enlarged view of the selected portion in FIG. 6;

FIG. 11 is a perspective view of another state of the card wallet thereof;

FIG. 12 is a perspective view of another state of the card wallet thereof;

FIG. 13 is a perspective view of another state of the card wallet thereof; and,

FIG. 14 is an enlarged view of the selected portion in FIG. 2.

The broken lines shown in the drawings depict portions of the card wallet in which the design is embodied that form no part of the claimed design. The dash-dot-dash broken lines shown in FIGS. 1, 6, 9, and 10 depict cut lines and form no part of the claimed design.

1 Claim, 14 Drawing Sheets
